US0D1100505S

(12) **United States Design Patent** (10) Patent No.: **US D1,100,505 S**
(45) Date of Patent: ** Nov. 4, 2025

(54) **BAG ACCESSORY CONNECTOR**

(71) Applicant: **Lane Life Designs, LLC**, Madeira, OH (US)

(72) Inventors: **Heather L. Riggelman**, Madeira, OH (US); **Meggin N. Musser**, Madeira, OH (US)

(73) Assignee: **Lane Life Designs, LLC**, Madeira, OH (US)

(**) Term: **15 Years**

(21) Appl. No.: **29/872,380**

(22) Filed: **Mar. 12, 2023**

(51) LOC (15) Cl. **08-11**

(57) **CLAIM**

The ornamental design for a bag accessory connector, as shown and described.

DESCRIPTION

FIG. 1 is a front perspective view of a bag accessory connector, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The figures include surface shading, which represents contour and not surface ornamentation.

1 Claim, 7 Drawing Sheets
